COMBINED PUMP AND METER

Leighton Dunning, Philadelphia, Pa., assignor to William M. Wilson's Sons, Inc., Lansdale, Pa., a corporation of Pennsylvania

Application September 14, 1954, Serial No. 32,278

Term of patent 14 years

(Cl. D65—1)

The figure is a front perspective view of a combined pump and meter embodying my new design.

The other side of the meter is like the side shown, and the back is plain.

I claim:

The ornamental design for a combined pump and meter, as shown and described.
